US0D1046311S

(12) **United States Design Patent** (10) **Patent No.:** **US D1,046,311 S**
(45) **Date of Patent:** **** Oct. 8, 2024**

(54) **SLEEVE FOR A DESCENT CONTROLLER**

(71) Applicant: **Tech Safety Lines, Inc.**, Carrollton, TX (US)

(72) Inventor: **Johnny Dickson**, Van Alstyne, TX (US)

(73) Assignee: **Tech Safety Lines, Inc.**, Carrollton, TX (US)

(**) Term: **15 Years**

(21) Appl. No.: **29/840,037**

(22) Filed: **May 25, 2022**

Related U.S. Application Data

(63) Continuation-in-part of application No. 29/709,731, filed on Oct. 16, 2019, now Pat. No. Des. 957,743.

(57) **CLAIM**

The ornamental design for a sleeve for a descent controller, as shown and described herein.

DESCRIPTION

FIG. 1 is a front perspective view of the sleeve for a descent controller;

FIG. 2 is a bottom perspective view of the sleeve for a descent controller;

FIG. 3 is a front view of the sleeve for a descent controller;

FIG. 4 is a rear view of the sleeve for a descent controller;

FIG. 5 is a left elevation view of the sleeve for a descent controller;

FIG. 6 is a right elevation view of the sleeve for a descent controller;

FIG. 7 is a top elevation view of the sleeve for a descent controller; and,

FIG. 8 is a bottom elevation view of the sleeve for a descent controller.

The broken lines illustrate portions of the environment illustrate portions of the sleeve for a descent controller. None of the broken lines form part of the claimed design.

1 Claim, 7 Drawing Sheets
